United States Patent [19]

Pollard

[11] Patent Number: Des. 428,138
[45] Date of Patent: ** Jul. 11, 2000

[54] MASK RETAINER PLATE

98/04310 5/1998 WIPO .

[76] Inventor: **Raymond James Pollard**, P O Box 481, Capalaba, Queensland, 4157, Australia

Primary Examiner—Stella Reid
Assistant Examiner—I Simmons

[**] Term: **14 Years**

[57] **CLAIM**

[21] Appl. No.: **29/088,544**

The ornamental design of the mask retainer plate, as shown and described.

[22] Filed: **May 27, 1998**

DESCRIPTION

[30] **Foreign Application Priority Data**

FIG. 1 is a front elevational view of a face mask retainer plate showing my new design, the rear elevational view being flat and unornamented;

Dec. 12, 1997 [AU] Australia 4021/1997
Apr. 2, 1998 [AU] Australia 956/1998
Apr. 3, 1998 [AU] Australia 957/1998

FIG. 2 is side elevational view thereof;

[51] LOC (7) Cl. **29-02**

FIG. 3 is a top perspective view thereof;

[52] U.S. Cl. **D24/110.1**

FIG. 4 is a side elevational view thereof, opposite that shown in FIG. 2;

[58] **Field of Search** D24/110.1; 129/206.24, 129/206.25, 205.25, 207.11, 205.24

FIG. 5 is a top plan view thereof;

[56] **References Cited**

FIG. 6 is a bottom plan view thereof;

U.S. PATENT DOCUMENTS

FIG. 7 is a front elevational view of a second embodiment of a face mask retainer plate showing my new design, the rear elevational view being flat and unornamented;

4,907,584 3/1990 McGinnis 128/206.24
